A. J. DONLEY

ADJUSTABLE SECTIONAL FORM

Filed March 10, 1924

INVENTOR.
ALFRED J. DONLEY

G. H. Bradcock
ATTORNEY.

UNITED STATES PATENT OFFICE.

ALFRED J. DONLEY, OF BRIDGEPORT, CONNECTICUT.

ADJUSTABLE SECTIONAL FORM.

Application filed March 10, 1924. Serial No. 698,200.

To all whom it may concern:

Be it known that ALFRED J. DONLEY, a citizen of the United States, and resident of Bridgeport, in the county of Fairfield and 5 State of Connecticut, has invented certain new and useful Improvements in Adjustable Sectional Forms, of which the following is a specification.

This invention relates to an adjustable 10 sectional form for the casting of concrete walls, footings in connection with walls, concrete beams, offset walls, cornices, piers, concrete chimney breasts, concrete chimneys, and the like. As a form for cellar walls, or 15 for side walls above a cellar, or for other walls, it can be used for the casting of walls with square angled corners, and for casting of walls with acute or obtuse angles, such as angles for bay windows.

20 In the single embodiment of the invention illustrated in the drawing and hereinafter described, I have preferred to set forth a construction of sectional form adapted to the casting of cellar walls. However, it 25 will be understood that the functioning principles of the novel form are the same when used for piers, cornices, or walls different from cellar walls.

The present sectional form can be used for 30 a single face or side wall, or for two sides of a wall, the form providing the means for casting the entire wall including the footings which are wider than the wall proper. That is to say, two sets of forms in which 35 the features of the invention are incorporated can be utilized to cast the two sides of a wall, a functioning feature of this double set of forms, an inside and an outside set, being that panels and posts can be erected 40 not touching at the bottom where the wall is to be cast. Said panels and posts can be kept up free any height, say six inches, so that a footing course of concrete can be cast, the footing being adapted to extend 45 under the posts and panels beyond the inner and outer faces of a wall defined by the oppositely disposed panels. This enables the footing to be cast at the same time as the wall proper.

50 The broad object of the invention is to

provide a sectional form for the casting of concrete walls and the like which will be an improvement generally over all forms of the same general character heretofore known, and will at the same time be capable of being produced and set up for use, and for re-use at recurring intervals, at expense much less than any sectional form heretofore known and with which I am familiar.

55 A more specific object is to provide a novel and adjustable sectional form which can be easily and quickly adjusted to suit the dimensions of a cellar plan.

60 A further specific object is to provide an adjustable sectional form of the present 65 character which will include concrete-retaining panels and novel concrete-retaining members or angle pieces associated with said panels and adapted to the purpose of allowing movement relatively to each other 70 of units of said sectional form, each unit including a panel or panels, whereby the form as a whole is adjustable to be exactly and quickly set to suit the dimensions of a 75 plan, as will become obvious.

Another specific object is to provide a 80 novel concrete-retaining member or angle piece adapted to lie contiguous with separate panels of a sectional concrete form and between said panels and concrete being cast, 85 to span the space between said separated panels and to touch both panels the entire length of said member or angle piece, and to furnish said concrete-retaining member or angle piece with a web or webs adapted to 90 extend between said panels, by or adjacent to a post or the like, or a plurality of posts, against which the panels are adapted to be secured, away from said concrete being cast, to be securely held against said post or posts 95 by a clamping member, whereby said concrete-retaining member or angle piece can engage the panels at locations spaced variable distances from said web or webs in order that the panels at the opposite sides 100 of the web or webs can be spaced at variable distances apart, thus rendering the separated panels adjustable toward and from each other, without destroying the effectiveness of the sectional form for its intended

purpose. Clearly, each panel may be a unit of the sectional form, or it may be a part of a unit including a plurality of panels secured together, and by adjusting the various units in the manner briefly stated, the form as a whole is rendered adjustable, within limits, to suit the dimensions of any plan of concrete to be cast.

And yet another specific object is to provide a double set of forms adapted to the purpose of casting both sides of a wall or the like, the forms being constructed to constitute the means for casting the entire wall including footings wider than the wall proper, the whole structure comprising an arrangement whereby panels and posts can be erected at an elevation above a bottom wall or footing to be cast, so that concrete poured or otherwise placed in the space between the two sets of forms can extend under the panels and posts outwardly beyond the confines of the concrete-retaining faces of said panels; that is, the novel double set of sectional forms is adapted to allow the footing to be cast at the same time as is the wall confined between the oppositely disposed panels of the different sets of forms.

With the above objects in view, as well as others which will become obvious as the specification proceeds, the invention comprises the construction, arrangement and combination of parts as now to be fully described and as hereinafter to be specifically claimed, it being understood that the disclosure herein is merely illustrative of principles of the invention and meant in no way in a limiting sense, changes in details of construction and arrangement of parts being permissible so long as within the scope of the appended claims.

In the accompanying drawing forming a part of this specification.

Fig. 1 is a sectional view of fragments of a double set of adjustable sectional forms in which the features of the invention are incorporated, taken as on line 1—1 in Fig. 2;

Fig. 2 is a sectional view as on line 2—2 in Fig. 1;

Fig. 3 is a sectional view as on line 3—3 in Fig. 1; and

Fig. 4 is an enlarged perspective view of the novel concrete-retaining member or angle piece, the lower portion of the member or piece being broken away, showing the member or piece as in Fig. 2 in full lines, and each corner member as in Fig. 1 in dotted lines.

Generally speaking, the present adjustable sectional form consists of posts, panels, battens, concrete-retaining members associated with the panels and posts, devices for locating the concrete-retaining members, and girts or string pieces.

With respect to the drawing and the numerals of reference indicated thereon.

denotes units of the adjustable sectional form, each unit consisting of panels 11 arranged side by side contiguous with each other, and battens 12 to which the panels are secured in any convenient manner, the battens serving to insure the fixed location of the panels of a unit relatively to each other. A unit may be a single panel, but preferably it consists of a plurality of panels connected by battens. The faces of the panels opposite the battens are adapted to serve as concrete-retaining surfaces; that is, said faces are adapted to be engaged by concrete being cast.

The posts, the concrete-retaining members (or angle pieces), and their associated parts, and the girts or string pieces are for the purpose of associating the several panel units with each other to render them capable of serving their intended function, and certain of the concrete-retaining members or angle pieces serve the additional purpose of spanning the spaces between panels of different units (1) to effectually fill said spaces, and (2) to allow adjustment of adjacent panel units toward and from each other, whereby a sectional form as a whole is adjustable to suit dimensions of some particular plan of concrete to be cast.

In Fig. 1 of the drawing, I have disclosed an inner and an outer sectional form. In the case of each form there is shown a corner post 13, an intermediate post 14, and an ordinary or reinforcing post 15.

Each intermediate post 14 is situated at a location where panel units terminate adjacent each other. As illustrated, an intermediate post consists of two timbers with a board between, the timbers and board being bolted together as by means of the bolts 16. Holes 17 through the posts 14 are for a purpose to be described.

The corner posts 13 likewise each consist of two timbers with board between, and these posts also have holes 17.

The ordinary or reinforcing posts 15 may be of any suitable construction.

As very clearly shown in Fig. 1, the faces of the panel units having the battens are adapted to be in firm engagement with adjacent faces of the posts 13, 14 and 15, and to this end said post faces are desirably flat as disclosed. Girts or string pieces 18 are adapted to engage directly against the face of each post 15 opposite the panel units, and to engage plates 19 themselves in engagement with the faces of the posts 13 and 14 opposite said panel units and preferably secured to said posts 13 and 14, means being utilized at the location of said posts 13, 14 and plates 19 for securing the panel units to the posts 13, 14, and for securing said posts to the girts or string pieces 18, these girts or string pieces, as shown, preferably extending the full distance about the

sectional form, it being understood that in the case of a rectangular structure of concrete to be cast, each adjustable sectional form is rectangular in plan, the outer form 5 extending completely about the inner form when a double concrete wall is to be cast, the illustration of Fig. 1 merely displaying elements of the whole double set of sectional forms which are to be merely duplicated in 10 a whole double set of forms.

Of the means for retaining the panel units to the posts 14, and for clamping said panel units, posts 14 and girts 18 to each other, 15 denotes concrete-retaining members or angle pieces the inner faces of which are adapted to lie between the panel units and concrete to be cast and the outer faces of which are adapted to engage the panel units, each leg 21 of a concrete-retaining member 20 or angle piece 20 engaging a different panel unit for its full length. Fig. 4 more clearly discloses the exact construction of these concrete-retaining members or angle pieces. Secured, preferably centrally, to the outer face 25 of each member or piece 20 is a web or webs, denoted 22, these webs being adapted to lie in the holes 17 through the posts 14, and having perforations 23. Numeral 24 denotes bolts each of which has a threaded end 25 and a double bend 26 opposite the thread adapted to be removably hooked or locked into a perforation 23 of a web 22. Each bolt extends through a post 14 and through a plate 19 set on the outer side of the post, as 30 explained, and continues, passing through a face plate 27, this face plate coming into contact with flanges 28 bent outward from the plate 19 which is itself fastened to the outer side of a post 14. The girts 18 extend over the outer faces of the plates 19 and are situated between the flanges 28, while the face plates fit against the outer faces of the girts, as will be best understood from 35 Figs. 2 and 3. In said figures it will be seen that the bolts 24 pass through the plates 19 and 27 at a location spaced from the girts, so that, evidently, the posts 14 and the plates 19, 27 are adjustable along the lengths of 40 the girts. Numeral 29 represents handles 50 each having a thread screwed onto a bolt 24 and adapted to come into contact with a face plate 27, so that each handle when turned inwardly on a bolt (as in clamping the panel units, the posts and the girts to each other), draws the bolt and concrete-retaining member or angle piece outward, and when turned in opposite direction moves 55 the member or angle piece away from the panel units and posts.

Without the necessity for further explanation, it will now be apparent that the posts 14 can be adjusted to any desired positions along the girts 18, and that adjacent panel units can be fastened against said posts 14 60 at different distances apart—at different dis-

tances away from the webs of the concrete-retaining members or angle pieces, so long as the opposite legs of the members or pieces engage the inner faces of the different panel units for their full lengths to preclude the 70 passage of concrete through the spaces between panel units. Thus, there is a capability of adjustment of the panel units relatively to each other to meet various conditions, such as the warping of the material 75 of the panels, which is preferably wood, to allow the sectional form to be exactly and quickly set to suit the dimensions of a particular plan. It is to be remarked that the panel units can be suspended from the posts 80 13, 14, or 15 in any ordinary or preferred manner, suiting the conditions, until the clamping devices have been manipulated to clamp the panel units, posts and girts to each other, all as will be understood. Naturally, the widths of the posts 15 are the same 85 as the widths of the posts 14, so that clamping the panel units and the girts to the posts 14, also clamps said units and girts to the posts 15. Or where it is desirable, special 90 securing means may be utilized to secure the panels to the posts 15.

At the corners of the forms the construction for clamping the panel units, the posts 13 and the girts 18 to each other is substantially as already described, except that the concrete-retaining members or angle pieces are of slightly different shape, as may be the posts 13, the plates 19 and the facing plates 27, and that, usually, at the corners there is no necessity for the provision of means allowing for adjustability of the panels relatively to each other. Here the panel units can be relatively fixed, the adjustability of the sectional forms being cared for as already described. At the outer corner the plates 19 and 27 may be duplicates of the plates described, while at the inner corner said plates are of a trifle different construction, it being sufficient to state that all of 100 these plates are of a configuration best suitable to properly retain end portions of the girts 18.

While the angle piece 30 at the inner corner has a right-angle bend with the webs at 115 the center of the angle, the angle piece 31 at the outer corner has a right-angle bend with the webs extending away from the bend at the center of the angle, and both the inner and outer posts 13 are shaped to provide the 120 desired inner and outer corners of the sectional form, as will be apparent.

The concrete-retaining members or angle pieces 20, 30 and 31 are, on their inner or wall side a part of the form or mold in contact with the concrete, the remainder of the form or mold being the inner or wall side of the panels. The angle pieces 20 leave a flattened V-shaped perpendicular crease in the concrete, and since the angle pieces, as 130

well as the posts, are spaced at regular intervals about the form or mold, the crease repeated gives a paneled effect to the wall. At the corners the angle pieces 30 and 31 will ordinarily likewise leave wholly sightly creases in the cast concrete.

The angle pieces and their webs are desirably welded together so that each angle piece is a single unit. The shapes of the angle pieces may be changed to meet the conditions as they may occur in practice. I have preferred to show three different shapes (see Fig. 4).

With more especial reference to Figs. 2 and 3, I have here disclosed one manner in which the posts and panels can be elevated above a footing or the like to be simultaneously cast with a main wall. Numeral 32 denotes a form or mold to receive concrete to provide a footing beneath a wall at the left hand side of the panels of Fig. 3, it being understood that the structure disclosed would be duplicated beyond and opposite said panels to cast a two-wall construction. Numeral 33 represents a nailing piece secured to a post 14 as by means of the bolts 34, and 35 indicates a pipe or the like fixed in a bar 36 and removably engaging said post 14. The opposite end of this bar is secured as at 37 to a peg 38 driven into the material 39 which may or may not be the material of the form or mold 32. A rest 40 beneath the bar 36 and upon the material 39 serves an obvious purpose. Numeral 41 denotes a brace secured to the bar 36 as at 42 and adapted to be secured to the upper portion of a post 14. In Fig. 2, 43 denotes a brace which may also support the upper portion of a post, a post 14 as shown. These braces may be secured directly to the posts, or may be secured to nailing pieces upon the posts.

A double set of forms, one of which is shown in Fig. 3, are, evidently capable of simultaneously casting a wall confined between opposite panels of the adjustable form and a footing for said wall.

The sectional form of the present invention can be originally produced and set up for use, and re-set up for use at recurring intervals, at relatively small expense. The adjustable features of the form make it quickly and easily adaptable to suit dimensions, no matter what may have been the tendency of panel units to warp over long periods.

Having thus fully described the invention, what I claim as new and desire to secure by Letters Patent is:

1. In a form of the character described, a post, spaced apart panel units, a concrete-retaining member adapted to hold said spaced apart panel units to said post, said member consisting of an angle piece having legs, each leg being adapted to engage

a different panel unit for its full length, and means for releasably clamping said concrete-retaining member, said panel units, and said post to each other in such manner that the panel units can be adjustable from 70 and toward each other and with respect to said post.

2. A form of the character described, comprising posts, panel units, angle pieces adapted to hold said panel units to said 75 posts, each angle piece having a web extending adjacent a post, and a clamping device detachably secured to each of said webs and adapted to releasably secure said angle pieces, panels, and posts to each other. 80

3. In a form of the character described, a post, spaced apart panel units, a girt, said girt and panel units being adapted to be clamped to said post, and a concrete-retaining member adapted to hold said panel units 85 and said girt to said post, said member including legs each adapted to engage a different panel unit, and means for releasably clamping said member against said panel units and said girt against said post, whereby said panel units can be adjustably and removably secured to said post. 90

4. In a form of the character described, a post, spaced apart panel units, a girt, said girt and panel units being adapted to be 95 clamped to said post, and a concrete-retaining member adapted to hold said panel units and said girt to said post, said member consisting of an angle piece having legs each adapted to engage a different panel unit for 100 its full length, and means for releasably clamping said member against said panel units and said girt against said post, whereby said panel units can be adjustably and removably secured to said post. 105

5. A form of the character described, comprising posts, panel units, girts, angle pieces adapted to hold said panel units and girts to said posts, each angle piece having a web extending adjacent a post, and a clamping 110 device detachably secured to each of said webs and adapted to releasably secure said angle pieces, panels, and girts to said posts.

6. The combination as specified in claim 5, wherein there are flanged plates secured to certain of said posts and said girts lie within said flanged plates, certain of said posts being adjustable along the lengths of said girts. 115

7. In combination with a fixed form for casting a footing beneath a main wall, said footing being of greater width than said main wall, a double set of forms of the character described, and means for positioning said double set of forms above said fixed form for casting said footing, whereby said main wall and footing can be simultaneously cast. 120

8. A double set of spaced apart forms each consisting of posts, panel units, and means 130

for releasably and adjustably securing said panel units to said posts, said double set of forms being adapted to the casting of a main wall, in combination with a fixed form beneath said spaced apart forms and adapted to the casting of a footing of greater width than said main wall, and means

for positioning said double set of forms above said fixed form.

Signed at Bridgeport, in the county of 10
Fairfield, and State of Connecticut, this
8th day of March, A. D., 1924.

ALFRED J. DONLEY.
